CLAIM

The ornamental design for a vessel assembly, as shown and
described.

DESCRIPTION

FIG. 1 is a perspective view of a vessel assembly according
to our new design;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.

The broken lines immediately adjacent the shaded areas
represent the bounds of the claimed design while all other

(Continued)

broken lines are directed to environment and are for illustrative purposes only; the broken lines form no part of the claimed design.

1 Claim, 7 Drawing Sheets

Related U.S. Application Data

a continuation of application No. 29/528,570, filed on May 29, 2015, now Pat. No. Des. 796,687, which is a continuation of application No. 29/449,681, filed on Mar. 15, 2013, now Pat. No. Des. 731,672, which is a continuation of application No. 29/418,181, filed on Apr. 12, 2012, now Pat. No. Des. 690,826.
